(57) **CLAIM**

The ornamental design for an inkjet printer, substantially as shown and described.

DESCRIPTION

FIG. 1 is a perspective view of an inkjet printer in accordance with the present invention;

FIG. 2 is a top plan thereof;

FIG. 3 is a front elevational view thereof;

FIG. 4 is a rear elevational view thereof; and,

FIG. 5 is a right side elevational view thereof, the mirror image of which is the left side elevational view thereof.

1 Claim, 4 Drawing Sheets

FIG.2

FIG.5
